UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

PRINTING-PLATE AND SUPPORT THEREFOR.

1,282,923.

Specification of Letters Patent. Patented Oct. 29, 1918.

Application filed May 20, 1916. Serial No. 98,913.

To all whom it may concern:

Be it known that I, EMIL E. NOVOTNY, a citizen of the United States, residing at Riverside, in the county of Cook and State 5 of Illinois, have invented certain new and useful Improvements in Printing-Plates and Supports Therefor, of which the following is a specification.

The present invention relates to certain 10 novel and useful improvements in printing plates and means for supporting the same in operative position on the printing press. My invention is applicable to and adapted for flat plates such as are used in connection with bed 15 and platen printing presses, or for curved plates such as are employed in rotary presses, and while I have in the present instance shown and described my invention as embodying, among other features, a printing plate made 20 from a composition such as a phenolic condensation product, I wish it to be understood that it is not limited in its useful application to a plate or plates of this character.

In carrying out my invention I propose to 25 provide a saddle or printing plate support which may be quickly and accurately fitted to the press, said saddle being constructed or equipped with means adapted to coöperate with complementary means on the printing 30 plate so that the latter may be readily, firmly and conveniently secured or fastened in exactly the proper position for printing purposes.

With the above recited objects and others 35 of a similar nature in view, my invention consists in the construction, combination and arrangement of parts set forth in and falling within the scope of the appended claims.

In the accompanying drawings:

40 Figure 1 is a transverse, vertical, sectional view taken through a segment or portion of the cylinder of a printing press equipped with my saddle and plate.

Fig. 2 is a detail cross-sectional view of 45 the saddle shown in Fig. 1.

Fig. 3 is a similar view of the plate.

Fig. 4 is a bottom plan view of a portion 50 of the printing plate.

Fig. 5 is a top plan view of a portion of 55 the saddle.

Fig. 6 is a cross-sectional view taken through a modified form of the invention which embodies a flat plate and saddle.

Before entering into a detailed description 55 of my invention I will state briefly that in

its preferred form it embraces, among other features, a saddle or support for the printing plate which is preferably formed of metal, such as aluminum, for example, this saddle preferably having formed in its upper or top face a series of small depressions or sockets spaced predetermined distances apart, these depressions or sockets being adapted to receive small complementary bosses or projections formed on the under 60 side of the printing plate, these bosses of the printing plate being, of course, spaced apart to correspond to the spacing of the sockets of the saddle. The saddle is provided also with countersunk screw bores opening into 65 the sockets, while the bosses of the printing plate are likewise provided with screw bores adapted to align with the bores of the sockets so that the plate may be screwed to the saddle. This is simply the preferred form 70 of the invention as, of course, it will be understood that if desired the plate might be formed with the sockets and the saddle with the bosses, and in some instances the bosses and sockets might be omitted altogether and 75 80 other clamping or fastening devices employed for connecting the plate to the saddle. Furthermore, I have herein, by way of illustration, shown the application of a single plate to a single saddle, but it will, of course, 85 be understood that a plurality of plates, or a number of sections may be secured to the saddle, and if necessary, the saddle may be made in sections.

Referring now to the accompanying drawings in detail, the letter A indicates the saddle as an entirety in the form shown in Figs. 1 to 5, inclusive. This saddle is in the nature of a plate curved or bent to correspond to the curve of the printing press 90 cylinder B, to which it is secured by screws 1 which pass through countersunk bores or screw-holes 2, suitably located, preferably adjacent the end edges of the saddle. This saddle is preferably made from a metal such 95 as aluminum and is cast with a series of small sockets or depressions 3 in its upper face, these sockets being preferably arranged in rows and spaced equidistant apart. Opening through and into each socket is a 100 screw-bore 4, which also opens through the bottom or back of the saddle, the end of the bore opening into the socket being reduced and tapered as at 6, to snugly receive the 105 head of the, preferably, hollow screw 7, the 110

shank of which, when the screw is in place, projects centrally through the socket, and is adapted to be threaded into an adjacent boss on the printing plate, as will herein-after appear.

The printing plate in Figs. 1 to 5 is designated as a whole by the letter C, and is preferably in the nature of or formed from a composition such as a phenolic condensation product, that is to say, a product having as constituents phenol and formaldehyde. There are a number of these phenol products known in the art, one of which is known as "bakelite." A printing plate made 10 from such a composition or product possesses manifest advantages from the standpoint of durability, rigidity, uniformity under variations in temperature, capability of withstanding the stresses and strains 15 encountered in the printing operation and will present sharp, clear type outlines, thus insuring clean, attractive work.

This printing plate C is cast in a suitable mold, so constricted as to form series or 20 rows of small bosses or projections 8 on the back of the plate, these bosses or projections being complementary as to the sockets of the saddle, are spaced the same or equal and uniform distances apart, as are the 25 sockets of the saddle, and are of dimensions to fit snugly within the socket. In the casting of the plate each boss is formed with a threaded bore 9 adapted to aline with the bore in the socket in which the boss seats, 30 this bore 9 being adapted to receive the shank of the screw 7 so that the plate may be secured to the saddle. It is, of course, to be understood that the plate is curved or bent to correspond to the curvature of the 35 saddle. Thus, in applying the plate to the saddle, it is only necessary to line up the bosses of the plate in the sockets of the saddle and thread in the screws.

The majority of the bosses, as well as the 40 majority of the sockets of the saddle, are substantially circular in cross-dimension, horizontally, but I preferably form the socket of the rows adjacent the side edges of the saddle elongated as shown at 10, and 45 I likewise elongate the bosses of the rows adjacent the side edges of the plate, as shown at 11, to correspond with the elongated 50 sockets in which they are to fit, screws also being employed for securing the elongated

bosses in the elongated sockets. This elongation of the bosses and sockets at the side edges of the plate and saddle, respectively, enable me more readily to apply and remove a maximum size plate from its saddle.

In Fig. 6 I have shown a cross-section of 60 a slightly modified form of the invention, in this case a flat saddle plate B', and upon which is to be fitted a flat printing plate C'. This flat saddle plate B' is also provided with a series, or rows, of sockets or depressions 12 for the reception of complementary bosses 13 formed on the under side of the flat plate, the screws 14 being employed as a fastening means.

It will be noted that I provide a means for 70 quickly applying a plate to the press without employing hooks or the like, which tend to weaken the structure, and my invention will hold the plates snugly down on the cylinder without producing bulges or the 75 like.

While I have herein shown and described the preferred embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. The combination with a support, of a printing plate adapted to be attached thereto, and means, including uniformly spaced, complementary depression and projections, 90 for insuring the selective fitting of the plate on the support, certain of the depressions and projections being of elongated formation.

2. The combination with a saddle adapted 95 to be mounted upon a printing press and having a series of equi-distant spaced sockets formed in its outer face and a series of screw bores opening into said sockets, a printing plate having a series of similarly spaced 100 bosses formed on its back face and adapted to fit into the sockets of the saddle, the said bosses having screw bores adapted to aline with the bores of the saddle, and screw members seated in the bores and fastening the 105 plate to the saddle.

In testimony whereof I affix my signature.

EMIL E. NOVOTNY.
